GOLF BAG

Original Filed Oct. 17, 1922

FIG. 1

FIG. 2

FIG. 3

→ 5 FIG. A

FIG. 5

INVENTOR:

46
John E Schank

By John Howard (McElroy)
HIS ATTY.

UNITED STATES PATENT OFFICE.

JOHN EDWARD SCHANK, OF CHICAGO, ILLINOIS, ASSIGNOR TO R. H. BUHRKE CO., OF CHICAGO, ILLINOIS, A CORPORATION OF ILLINOIS.

GOLF BAG.

Original application filed October 17, 1922, Serial No. 595,044, and in Canada November 2, 1922. Divided and this application filed November 14, 1924. Serial No. 749,828.

My invention is concerned with golf bags, and more especially with a ball pocket for such bags so constructed that the balls cannot accidentally work out of the pocket, and which can be quickly locked so that the balls cannot be stolen therefrom without cutting it open or defacing it in a manner that would be immediately noticed.

This application is a division of my application No. 595,044, filed October 17, 1922.

To illustrate my invention, I annex here-to a sheet of drawings, in which the same reference characters are used to designate identical parts in all the figures, of which,—

Fig. 1 is a side elevation of a golf bag having my invention applied thereto;

Fig. 2 is a perspective view of a portion of the pocket on an enlarged scale;

Fig. 3 is a plan view of the locking mechanism without the bag;

Fig. 4 is a section on an enlarged scale, on the line 4—4 of Fig. 1; and

Fig. 5 is a section on the line 5—5 of Fig. 4.

My invention can, of course, be applied to any sort of a golf bag, and it will be seen from the drawings that I rivet to the body material 11 just above the open end of the pocket 40, which otherwise may be of an ordinary construction, the spring strip 41 and the metal strip 42, preferably by a single set of rivets 43. The spring strip 41 has riveted in the center thereof the metal lug

44, which has a flat top, on which rests the inverted T-shaped end 45 of the locking eye 46, which may be conveniently stamped up from a piece of sheet metal. The eye is supported in place, either in the erect, full-line position shown in Fig. 5, or in the turned-

down position shown in dotted lines, by the preferably rotatable eyelet 47, which is circular in its general outline, with its outer portion of a rather flattened, truncated, conical shape, while in its center is the oblong

elevation 48 adapted to accommodate the T-shaped end 45 in either position, the shank passing through the aperture 49 formed in the eye, which aperture, for convenience of construction, preferably extends clear to the circumference, but with the outer portion 50 substantially narrowed so as to form shoulders co-operating with the shank. The central portion of the strip 42 is enlarged to

form the circular portion 51, and said portion is given the flattened conical shape 55 shown to co-operate with the eye 46, said central portion being, of course, provided with the aperture 52 through which the raised portion 48 of the eye extends. With the construction shown, it will be obvious that the eye can in its upright position, be rotated through a complete circle, as well as in its turned-down position, although in said turned-down position it does not need to be rotated. The top of the pocket 40, which is preferably reinforced by the leather binding 53, has riveted thereon the metal locking strip 54, which is provided with the slot 55 so located and shaped that when the strip 54 is brought toward the strip 42, the ring 60 of the eye 46 will pass through said slot 55, and when the bag is in use, it is secured 65 simply by turning the eye 46 to the position shown in Fig. 2, where it prevents any possible opening of the pocket so as to allow the balls to escape accidentally, and thus furnishes an insurance that if any balls are missing at the end of the round, the caddy is responsible for their actual removal, as they cannot escape accidentally. When the 70 round is completed, the padlock 56 has its hasp 57 slipped through the ring of the eye 46, and the bag can be sent to the shop with the certainty that none of the balls will be surreptitiously removed while in the shop, 75 and before the next game.

While I might make the eye simply rotatable without the ability to turn it down, as shown in dotted lines in Fig. 5, I prefer to so pivot it, as I have found by experience that the eye sticking out straight is somewhat of an obstacle when the hand is thrust down into the pocket to reach balls in the bottom thereof, whereas it does not interfere when it is turned down.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a bag, the combination with the body

thereof, of a rigid strip secured thereto, a ball pocket secured to the body and having its open end adjacent the strip, a second strip carried by the top of the pocket body parallel to and movable to and from the first strip, an eye permanently attached to the first strip, a slot in the second strip, and means for securing the strips together when the eye is passed through the slot, said eye being pivoted relative to the strip so it can be turned down substantially parallel thereto.

2. In a bag, the combination with the body thereof, of a rigid strip secured there-

to, a ball pocket secured to the body and having its open end adjacent the strip, a second strip carried by the top of the pocket body parallel to and movable to and from the first strip, an eye permanently attached to the first strip, a slot in the second strip, and means for securing the strips together when the eye is passed through the slot, said eye being pivoted in a member which in turn is rotatable in the strip.

In witness whereof, I have hereunto set 25
hand this 12th day of November, 1924.

JOHN EDWARD SCHANK.
